UNITED STATES PATENT OFFICE.

ELBERT J. HALL, OF BERKELEY, CALIFORNIA.

PISTON.

Application filed April 18, 1923. Serial No. 632,914.

This invention relates to pistons for internal combustion engines, and has for its object to reduce piston slap and to dampen the vibrations.

As is well known a piston expands more rapidly than its cylinder, due to the fact that its temperature becomes higher in operation. In consequence the piston has to have a loose fit when relatively cold in order to overcome excessive friction under normal operating conditions. Where an aluminum alloy piston is used in a cast iron cylinder the amount of clearance is so great as to cause excessive piston slap before the piston becomes heated up.

To overcome this I provide the piston with a movable segmental portion in the side of the skirt opposite that receiving the power stroke thrust and arrange a spring back of this movable segmental portion to yieldingly force the same outwardly. Not only does this movable segmental portion absorb the slap tending to occur in a direction at right angles to the axis of the wrist pin, but, if the width of the movable portion be extended to within a short distance of the pin bosses, any tendency of the piston to slap in a direction parallel with the axis of the wrist pin can be prevented. The action of this segmental portion can also be improved by utilizing oil to act as a check or cushion against inward movement of the said movable member.

In the accompanying drawings—

Fig. 1 shows a central, vertical, sectional view of the piston embodying one form of my invention.

Fig. 2 shows a plan sectional view of the same.

Fig. 3 shows a vertical, central, sectional view of a modified form of the piston.

Fig. 4 shows a plan sectional view of the form illustrated in Fig. 3.

The piston may be of any improved design and of any desired material. In that side of the skirt opposite the side receiving the thrust on the power stroke is a separate segmental portion 10 fitted slidably into a recess in the skirt of the piston. The outer surface of this segmental portion is ground on an arc of the same diameter as the cylinder bore. Back of the segmental portion is a light coil spring 11 abutting against the wall of the piston skirt and tending to force the movable segmental portion outwardly.

In the form shown in Figs. 1 and 2 this

segmental portion is provided with a chamber 12 in which the spring is seated and a duct 13 communicates with this chamber, said duct leading to the outside of the piston at a point immediately below the piston rings. Oil on the cylinder walls is thus admitted to the chamber 12 and acts as a check or cushion against inward movement of the segmental portion 10.

In Figs. 3 and 4, I show the piston cut away at one side and a separate segmental portion 14 slidably fitted into guides 15 surrounding said cut away portion. In this form of the invention I show a bowed leaf spring 16 abutting against the opposite wall of the piston and extending over the piston pin and pressing against the inside of the segmental portion 14.

In the operation of the piston the spring 15 forces the movable segmental portion outwardly against the cylinder wall when the thrust is acting in the opposite direction on the piston. As the piston rod passes over the center and the direction of the thrust is reversed the segmental portion will move inwardly against the spring. The effect of the heat is to weaken or lessen the resistance of the spring so that the spring may be comparatively stiff when the piston is relatively cool and of less resistance when the piston is hot. Thus the movable segmental portion will be held closely in contact with the cylinder wall when the piston is cool, while, at the same time, when the piston expands under higher temperatures, the spring will readily yield to allow the movable segmental portion to move inwardly.

In the form shown in Fig. 1, where the oil chamber 12 is provided, this chamber 95 will become filled with oil when the segmental portion 10 moves outwardly. The oil therein will act as a check or cushion against inward movement of the segmental portion. The tendency of the piston to slap 100 the cylinder walls will be overcome with the arrangement shown herein, and, likewise, vibrations occurring in the operation of the piston will be considerably damped.

The width of the movable segmental portion may vary, but by widening it to within a short distance of the pin bosses, as shown for example in Fig. 4, I am enabled to do away not only with slap in a direction at right angles to the wrist pin but also in a 110 direction parallel therewith. In other words, if the segmental portion be made to

cover about one-third the circumference of the piston the slap in all directions will be prevented.

I prefer to make the spring 16 of thermos-
5 static metal, that is, having an inner layer
16^a of less coefficient of expansion than the
outer layer 16^b. The effect of this is to
draw the spring in, when heated, and thus
10 lessen the outward pressure exerted by the
spring upon the movable segment when the
piston becomes hot.

It is to be noted that the movable seg-
ment terminates above the bottom of the
15 skirt of the piston so that the entire cir-
cumference of the lower part of the piston
skirt is left intact, thus preserving the
strength of the piston.

Various changes in the construction and
arrangement of the several parts herein
20 shown and described may be employed with-

out departing from the spirit of my inven-
tion as disclosed in the appended claim.

Having thus described my invention, what
I claim and desire to secure by Letters Pat-
ent is:—

25 A piston for internal combustion engines
having near its upper portion a groove for
retaining a scraper ring, a movable seg-
mental portion forming part of the piston
skirt, a chamber to contain oil arranged be-
tween the segmental portion and the wall
30 of the piston, and a duct leading from said
chamber to the outside of the piston adjac-
ent the scraper ring groove, whereby oil
scraped by the ring will be admitted to the
chamber for the purpose of forming a check
35 against inward movement of the segmental
portion.
